United States Patent

Des. 234,395
Patented Feb. 25, 1975

234,395

BOTTLE OR SIMILAR ARTICLE

Livingston C. Douglas, Leonia, N.J., assignor to Colgate-Palmolive Company, New York, N.Y.

Continuation-in-part of design application Ser. No. 246,517, Apr. 21, 1972. This application Sept. 28, 1972, Ser. No. 292,977

Term of patent 14 years

Int. Cl. D9—01

U.S. Cl. D9—125

FIG. 1

FIG. 2

FIG. 3

FIG. 1 is a top plan view of a bottle or similar article showing my new design;

FIG. 2 is an elevational view; and

FIG. 3 is a bottom plan view.

This application is a continuation-in-part of my earlier application Ser. No. D. 246,517 filed Apr. 21, 1972.

I claim:

The ornamental design for a bottle or similar article, as shown and described.
